DELTA COUPLING

Lars Fredriksson, Vaxjo, Sweden, assignor to K.A. Bergs
Smide AB, Gemla, Sweden

Filed Oct. 20, 1975, Ser. No. 623,743

Claims priority, application Sweden May 15, 1975

Term of patent 14 years

Int. Cl. D8—08

U.S. Cl. D8—229

FIG.1

FIG.2

FIG.3

FIG.4

FIG.5

FIG. 1 is a front view of a delta coupling showing my new design;

FIG. 2 is a perspective view of my delta coupling as seen from the right in FIG. 1;

FIG. 3 is a top perspective view of my delta coupling as seen from a point above the center thereof;

FIG. 4 is a rear view of my delta coupling, and

FIG. 5 is a perspective view of my delta coupling as seen from the right in FIG. 4.

I claim:

The ornamental design for a delta coupling, as shown and described.
